UNITED STATES PATENT OFFICE.

THEODORE H. MULCH, OF NEW YORK, N. Y.

INCANDESCENT LAMP-BURNER.

SPECIFICATION forming part of Letters Patent No. 593,231, dated November 9, 1897.

Application filed February 11, 1897. Serial No. 622,955. (No model.)

To all whom it may concern:

Be it known that I, THEODORE H. MULCH, a resident of the city, county, and State of New York, have invented an Improved Incandescent Gas-Burner, of which the following is a specification.

My invention relates to incandescent gas-burners, and has for its object to improve the same to provide an improved suspension device for the mantle.

My invention will be understood by referring to the accompanying drawings, forming part hereof, which illustrate a structure embodying my invention.

15 In the drawings, Figure 1 is an elevation of an incandescent gas-burner embodying my invention. Fig. 2 is an enlarged detail sectional view of the lower part thereof, the same showing the stop-cock arrangement. Fig. 3 is a view looking upward into the stop-cock, as clearly indicated by the arrow 3 in Fig. 2.

In the drawings, A is a mantle, B the burner-chamber, C the chimney-gallery, D the mixing-chamber, and E the stop-cock, of 20 an incandescent gas-burner, which may be all of the construction usual in such burners.

Branching out below the inlet-port e of the stop-cock is by-pass conduit G, which extends upward and terminates in proximity to the 25 side of the mantle in a burner g, which is adapted to throw a minute jet into proximity with the side of the mantle A. This by-pass conduit G is shown in Fig. 2 as bent or curved at the point g' and provided with a jacket g', in which a screw or other stopper g³ works to 30 regulate the flow of gas through the by-pass conduit. Any suitable regulating device for the gas may be used in lieu of the screw g³. By screwing the screw g³ in or out the flow of 35 gas through the by-pass conduit G may be regulated or entirely shut off.

Rising from the by-pass conduit G is a suspension-wire h, having a coil h' at its lower 40 end, which encircles the by-pass conduit, and 45 a hook h² at its upper end, which hook is a

suspension-hook for the mantle A. At some convenient point in the length of the suspension-wire h clips h³ are secured, which clips preferably embrace the burner-chamber B and prevent the mantle from wabbling—that 50 is to say, the clip shown on one side of the burner-chamber is duplicated on the other side of the burner-chamber and holds the suspension-wire or mantle-suspending device steady.

55 The suspension-wire, with its collateral parts, may be removed from the auxiliary burner, the coil h' sliding upward and off of the said auxiliary burner.

Having now described my invention, what 60 I claim, and desire to secure by Letters Patent, is—

1. In an incandescent gas-burner having a mantle, the combination with the said mantle of a suspension device therefor consisting of 65 a suspension wire or support h, a means at the lower end thereof for engaging a part of the gas-burner temporarily and removably, and clips h³ carried by the suspension-wire and secured thereto and adapted to engage a fixed 70 part of the gas-burner removably, so as to hold the suspension-wire steady, whereby the mantle may be supported by the gas-burner and be freely removable therefrom.

2. A mantle-support comprising the wire h 75 terminating at its upper end in a mantle-suspending device and at its lower end in a coil h' adapted to embrace an auxiliary burner, and having rigidly secured to said suspension-wire h a plurality of clips h³ adapted to embrace a fixed part of the burner whereby the said mantle-supporting device may be removably secured to an incandescent gas-burner, substantially as described and for the purposes set forth.

THEODORE H. MULCH.
